UNITED STATES PATENT OFFICE.

ROBERT C. CLARK, OF TACOMA, WASHINGTON.

CLEANING-MACHINE.

No. 890,405.

Specification of Letters Patent.

Patented June 9, 1908.

Application filed September 3, 1907. Serial No. 391,112.

To all whom it may concern:

Be it known that I, ROBERT C. CLARK, a citizen of the United States of America, residing at Tacoma, in the county of Pierce and State of Washington, have invented 5 certain new and useful Improvements in Cleaning-Machines, of which the following is a specification, reference being had therein to the accompanying drawing.

10 This invention relates to devices for brushing and cleaning articles, and has for its object to provide a mechanism whereby the articles may be cleaned without any handling. I attain this object by the mechanism and 15 devices illustrated in the accompanying drawing, in which

Figure 1 is a side elevation of my invention, a part of the shield being broken away to reveal the scouring or brushing mechanism. Fig. 2 is a vertical cross section of the operating motor, and Fig. 3 is a plan thereof.

Similar numerals of reference refer to similar parts throughout the several views.

This invention consists in a water or air 25 motor which drives a rotating brush, sponge, or other scouring means, and in which the waste air or water therefrom is conducted and sprayed around said rotated brush. A sliding shield is mounted thereon and surrounds 30 said rotated brush and the sprayer and prevents the splashing of the water or scattering of the dust from the cleansed article, said shield being elevated from the bottom to allow the air or water and the impurities carried thereby to pass away.

The handle 1 is secured to the center of the upper motor casing 2, the lower casing 3 being secured to said casing 2 by means of screws or other ordinary device, said casings 40 2 and 3 forming between them the round compartment in which the wheel 4 rotates. This wheel 4 is provided with a series of cavities cut in its outer edge, as illustrated in Fig. 3, and forming vanes adapted to receive the 45 impact of the air or water and to transform the same into rotary motion. The said wheel 4 is mounted on a vertical axis having an upper boss 5 extending upward into a hole in the upper casing 2, and a lower boss 6 extending downward therefrom and resting on the bridge 7 which engages the lower casing 3 and supports the rotating wheel 4. The shaft 8 is screwed into the wheel 4 through 50 the boss 6 from below and passes through a

hole in the center of the bridge 7 and transmits the rotary motion of the wheel 4 to the brush or sponge which is secured to its other end. The air or water is conducted through a suitable flexible hose 9 to the passage 10 formed in the side of the casing 2, said passage 10 leading to the inside of said casing at practically a tangent to the rotating wheel 4 so that the flow of the fluid in said passage 10 will strike the vanes formed on the wheel 4 at a sufficient angle and will cause them to 65 rotate. The cavity formed in the casings 2 and 3 is such as to allow plenty of room for the air or water to do its work on the wheel and then flow away around the arms of the bridge 7. The large pipe 11 is screwed into 70 the lower casing 3 and surrounds the shaft 8 and carries away the air or water from the motor. The pipe 11 has a cap 12 screwed to its lower end, said cap having a number of spray holes 13 around its lower end, through 75 which the air or water from the motor is sprayed on to the article being cleansed and on to the back of the rotating scouring brush. The bottom of the shaft 8 passes through the cap 12 and is screwed into the removable 80 frame 14 which carries the brush, sponge or other similar scouring means, said frame being properly shaped so that the brush will clean the article. A light shield 15 is mounted on the pipe 11 and is perfectly free to 85 move thereon, said shield being shaped so as to inclose the article being cleaned above it and all sides thereof, and being provided with suitable legs 16 so that it will be slightly elevated to allow the escape of the impurities 90 from this machine.

When water is used the vessel to be cleaned is usually placed in a sink and the machine is placed so that the brush will enter the vessel and so that the shield will cover it. The 95 pipe 9 is then attached to the faucet and the water turned on, causing the motor and with it the brush, to rotate rapidly and scour the sides and bottom of the vessel at the same time that the waste water from the 100 motor floods the vessel and carries away all the impurities. When the machine is used for cleaning windows or railway coach sides or carriages or other polished surfaces, a sponge is used with water. When the upholstery of a room, railway car, etc., is to be 105 cleaned, a suitable brush is used with air as the propelling force, the shape of the brush

being changed for these circumstances and the shield 15 may then be dispensed with if desired.

Having described my invention, what I claim is:

In a scouring machine the combination of a motor frame; a wheel having vanes formed thereon, and mounted within said frame, said frame being provided with a passage 10 adapted to convey a fluid under pressure against the vanes and thereby rotate the wheel; a shaft secured to said rotating wheel; a scouring means secured to the end of said rotating shaft; a waste pipe secured to said 15 frame and surrounding said shaft, and ex-

tending from the frame to the scouring means, and adapted to convey the fluid from the motor to and around the scouring means; a spraying attachment secured to said waste pipe, and adapted to spray the fluid on the 20 rotating scouring means; and a protective shield loosely mounted on the waste pipe and surrounding the scouring means, substantially as and for the purpose specified.

In testimony whereof I affix my signature 25 in presence of two witnesses.

ROBERT C. CLARK.
